UNITED STATES PATENT OFFICE.

GEORGE HAZELTON, OF BATTERSEA, LONDON, ENGLAND, ASSIGNOR TO VICKERS
LIMITED, OF WESTMINSTER, LONDON, ENGLAND.

MACHINE GUN.

Application filed July 30, 1920. Serial No. 400,203.

(GRANTED UNDER THE PROVISIONS OF THE ACT OF MARCH 3, 1921, 41 STAT. L., 1313.)

To all whom it may concern:

Be it known that I, GEORGE HAZELTON, a subject of the King of Great Britain, residing at R. A. F. Shops, Kirtling Street, 5 Battersea, in the county of London, England, have invented certain new and useful Improvements Relating to Machine Guns (for which I have obtained a patent in Great Britain, Serial No. 131,343, August 10 28th, 1919), of which the following is a specification.

This invention provides a device for registering and indicating the number of rounds fired by a machine gun.

15 With machine guns mounted on aircraft and other moving platforms it is particularly necessary for the gunner to know the number of rounds already fired when about to engage in aerial or other combat in order 20 that he shall not find himself suddenly run out of ammunition.

25 It has heretofore been proposed to operate a counting apparatus provided on a fire arm by means of the hammer thereof or by the pull of the trigger or by the recoil of the gun, by the inertia of a lever provided on the gun, this lever being under the control of a spring which is armed during the recoil and on the forward movement operates a pawl engaging a ratchet forming 30 part of a counting device, the ratchet being driven forward one tooth for each complete cycle of operations of the gun.

The invention consists in the combination 35 with a machine gun of a rounds counter operated from a reciprocating part of the gun by the interposition of a device comprising a spring push rod or the like, the spring or the like being armed during the recoil movement of the parts of the gun, and effecting on the return movement of the parts of the gun the rotation of the counter elements.

40 The accompanying drawings illustrate the invention applied to two known types of machine guns, Figures 1 and 2 being an end elevation and a sectional elevation on the line A—A of Fig. 1 illustrating the invention as applied to the Vickers machine gun, and Figures 3, 4 and 5 end elevation, part sectional elevation and inverted plan in part section illustrating the invention applied to the Browning gun,

similar parts being indicated by the same reference numeral.

55 In both constructions the counter 1 with its operating mechanism is carried as a unit on the back plate 2 of the gun this plate being hinged in the case of the Vickers gun and sliding vertically in the case of the Browning gun so that parts of the gear have to be modified accordingly to permit of the opening of the gun from the rear and withdrawal of parts of the gun without the counter and its operating parts preventing 60 or obstructing these operations.

65 Referring now to Figures 1 and 2, the shaft 3 of the counter has secured to it a toothed segment 4 meshing with a rack 5 formed on or carried by a rod 6 arranged 70 to slide but not rotate within a guide 7 such as by forming the whole or part of the rod of rectangular section to fit in a correspondingly shaped aperture or apertures 75 in the guide. The guide is secured such as by a flange 8 and bolts 9 to the back plate, and may as shown pass through an aperture formed in the back plate.

80 The guide is so positioned on the back plate that the forward end of the rod 6 is in proximity to one of the usual side or recoil plates of the gun, or other sliding reciprocating part indicated by the reference numeral 10, to which an angle bracket or other abutment 11 is secured, in such a 85 position that with the gun parts in their normal positions at rest, the abutment 11 and forward end of the rod 6 are just engaging. A spring 12 is mounted on the rod 6, the forward and backward movements of 90 which are limited by shoulders or collars 13, 14 engaging the forward end of the guide and a nut 15 closing the rear end of the guide.

95 The arrangement of the counter and its operating mechanism is so chosen, that in the recoil stroke of the gun the rearward movement of the abutment 11 forces the rod 6 to the rear compressing the spring 12 and by means of the rack 5 rotating the segment 4 and shaft 3 without the counter elements being rotated. On the return stroke of the gun, the compressed spring drives the rack 5 forward to rotate the segment 4 and shaft 3 in the reverse direction 100 to rotate the counter elements the required 105

angular amount to change the indicator to the next numeral in the well known way of counters. By this means the very quick and powerful blow of the recoil is not allowed to be transmitted to the counter mechanism.

It will be observed that by turning down the back plate and drawing back the rod 6 by hand, the rear of the gun is unobstructed, so that the parts of the gun which are customarily withdrawn and inserted from the rear end can be so dealt with.

Referring now to Figures 3 to 5 a bracket 16 is shrunk or otherwise secured to the casting 17 of the buffer carried by the back plate 2, and to this bracket is secured the counter 1 and a guide 18 for the rack 5, rod 6 and spring 12, the rack meshing with a toothed segment 4 on the shaft 3 of the counter, as hereinbefore described.

The forward end of the rod 6 is arranged to be normally flush with the inner face of the back plate, a collar 13 being provided to limit the forward movement of the rod to this extent, as it will be readily seen by an inspection of Figure 4.

Attached to an existing reciprocating part 19 of the gun such as by the pin 20 is a bent rod 21, guided by passing through a plate 22 which is drilled for this purpose, the rear end of the rod with the gun parts in their normal position of rest, just engaging the forward end of the rod 6.

The operation of the counter takes place in a manner similar to that above described.

What I claim and desire to secure by Letters Patent of the United States is:—

1. In a machine gun, the combination with a part of the gun moving automatically during firing, of a counter, a member inter-

posed between said part and said counter, a spring operating to effect movement of this member, during the return of the moving parts of the gun to the firing position after recoil, to operate the counter and means for arming said spring during the recoil movement of said moving part.

2. In a machine gun of the barrel recoiling type, the combination with a reciprocating part of the gun, of a counter, a member interposed between said part and said counter and a spring operating on said member to effect movement of this member, during the forward movement of the barrel after recoil, to operate the counter.

3. In a machine gun of the barrel recoiling type, the combination with a reciprocating part of the gun, of a counter, a member connected to said counter and arranged in loose contact with said part so that the latter moves said member rearwards during recoil of the barrel, and a spring operating on said member to effect movement of this member, during the forward movement of the barrel after recoil, to operate the counter.

4. In a machine gun of the barrel recoiling type, the combination with a reciprocating part of the gun, of a counter, a rack member arranged in loose contact with said part, a gear element which meshes with said rack member and is attached to the shaft of the counter and a spring operating on said member to effect movement of this member, during the forward movement of the barrel after recoil, to operate the counter.

In testimony whereof I affix my signature.

GEORGE HAZELTON.
